UNITED STATES PATENT OFFICE.

CASSIUS M. CARR, OF FORT WORTH, TEXAS.

DENTAL TOOL.

1,138,355.

Specification of Letters Patent. Patented May 4, 1915.

Application filed October 12, 1905. Serial No. 282,462.

To all whom it may concern:

Be it known that I, CASSIUS M. CARR, a citizen of the United States of America, residing at Fort Worth, in the county of Tarrant and State of Texas, have invented certain new and useful Improvements in Dental Tools; and I do hereby declare that the following is a full, clear, and exact description of the invention, such as will enable others to make and use the same, reference being had to the accompanying drawing, forming a part of this specification.

In carrying out my invention, I provide a series of tools each adapted for use upon a predetermined shaped portion of the tooth and each has a cutting edge and a guiding portion. The guiding portion serves to engage with the tooth in advance of the cutting edge to steady the same, while the cutting edge is in the line of the axis of the handle, whereby the instrument has no tendency to turn when in use and cuts after the manner of a Japanese plane.

The objects of my invention are, first, to remove calcareous deposits or scale from natural teeth, and effect the displacement of the calculi from any curved or irregular surface in the direct line of force applied in the drawing of the tool. Second. To plane the surfaces of the teeth so as to leave the surfaces perfectly smooth and induce the healthful condition of the surrounding tissue. Third. To adapt the tool to the sinuosities of the teeth and also provide for varying the position of the cutting blade in passing over the irregular surfaces, and, Fourth. To prevent injury to the tissue surrounding the teeth in the operation of the tool.

The invention accomplishes the removal of scale from the teeth, which scale results in the inflammatory conditions of the gum and pus formations and consequent loosening of the teeth, and which is known as "pyorrhea."

The construction of the tool will be first fully described and then its operation shown and the invention specifically pointed out in the claims.

In the drawings Figure 1 is a view of the novel tool showing the handle, the shank and its rounded end and cutting edge and its surface posterior to the cutting edge in perspective. Fig. 2 is a side view of the tool as seen in Fig. 1. Fig. 3 is an enlarged broken view in perspective of the outer end portion of the shank showing the cutting

blade. Fig. 4 is an end view of the tool enlarged showing the scale removing cutting edge of the tool and its position in relation to the longitudinal axis of the handle. 60 Figs. 5 and 6 are side and Fig. 7 a front view of the tool showing modifications of the shank. Figs. 8 and 9 are enlarged end views of the tool looking in the direction of the handle showing alternate positions of 65 the cutting edge of the tool to that seen in Fig. 4. Figs. 10 and 11 are enlarged views of upper molar teeth, and, Figs. 12, 13 and 14 are enlarged views of central incisors showing the application of the tool for the 70 removal of scale from the various portions of the teeth.

Similar numerals of reference indicate corresponding parts in all the figures of the drawing.

Referring to the drawings, 16 indicates the handle of the tool, the longitudinal surface of which for the purpose of illustration is octagonal in cross section; 17 indicates the bulge of the tool at the end of and in a direct 80 line with the handle. With the outer end of the bulge is connected the shank 18, of the tool which is bent laterally at said point of connection in a slight degree and then bent at a point smaller in circumference than the 85 bulge 17 and is bent intermediate its outer end and the bulge at an angle and said outer end extended to a position coincident with a direct line projected from and extending through the longitudinal axis of the handle 90 16, of the tool. The outer end back portion of the shank 18, is rounded and bent in a curved line or convexed at 19, to the said line extending through the longitudinal axis of the handle, and in a corresponding direction to the bent portion of the body of the shank 18 in the requisite degree. The surface of the face or forward concave portion 19^x of the said curved portion 19 is flat, the surface being excavated transversely with 100 an increased depth in a slight degree toward the cutting blade at the outer end of the shank. The extreme end of the curved portion 19, of the shank is bent or upset in an outwardly curved line of direction to said portion 19, forming a projection seen at 20, and extending forwardly of said concave portion 19, and the lower surface of said projection 20 extends transversely to the flat concave face surface 19 outwardly forming 110 the cutting edge 21, which edge extends to and is coincident with a line projected from

and extending through the longitudinal axis of the handle and in the position illustrated in Fig. 1 at an obtuse angle to the said line projected from said longitudinal axis of the handle. The tool as shown in Fig. 1 is provided with a long bent shank and an outer bent end forming compound curves or bends, available in the operation of removing scale from the lower third of the root of teeth, the length of which shank may be reduced when required for application to the upper third of a tooth and adjacent to the crown.

In operation the shank is introduced in the alveolar process with the cutting edge 15 of the tool directed toward the tooth and the scale and in order to effectively remove the scale the instrument is first directed to the lower third as seen in Fig. 12, for which the long shank in Fig. 1, with its concave excavated portion in contiguity with the root the concave surface of the shank posterior to the cutting edge bearing upon the side of the lower third of the tooth and a drawing movement imparted to the handle of the tool 20 in which movement the scale is attacked and dislodgment effected coincident with the posterior curved surfaces and when the scale is removed from the gum or process the operation is continued and upon the same surface 25 of the tooth from which the scale is removed until the entire surface of the dentine is perfectly smooth. In this operation the cutting edge of the tool being in line with the longitudinal axis of the handle the drawing movement meets no counteracting leverage 30 and this movement in the various positions of the handle may be performed with a slight grasp of the instrument by the hand, and at the same time a draw cut is imparted 35 to the scale and then to the surfaces of the tooth planing the surfaces until these surfaces are smooth. The results attained are readily appreciable and marked from the fact that in the use of the ordinary scale removing tool the cutting edges of these tools cause irregular engagements and leave the surface of the tooth in a rough condition. In 40 successfully removing the scale from various portions of the tooth the angle of the cutting edge 21 is conveniently varied as seen in Figs. 8 and 9, in which the cutting edges are shown disposed in coincident positions to the surface of the angles of the handle as shown octagonal and in cross section and in 45 series the varied positions are numerically the same.

In the modification as seen in Fig. 5 the portion of the shank posterior to the cutting edge of the tool is straight as at 27 and in 50 Fig. 6, the said end is formed with a convexed portion 22, posterior to the cutting edge and in Fig. 7 the flat concave surface posterior to the cutting edge is located upon the side of the shank. As before stated the 55 shank may be made long or short as the oc-

casion requires, the cutting edge always being upon the same side of the shank as the posterior flat surfaces. In order to remove the scale from the middle third of the tooth as seen in Fig. 13, the tool provided with the shank which is the modification as seen in Fig. 5 is employed, following which the scale is removed from the upper third as in Fig. 14, in which the modification of the tool as seen in Fig. 6 is employed to which the shank is particularly adapted, which being short in length the convexed excavated portions of the shank posterior to the cutting edge permit the cutting edge to enter the depression at the neck of the tooth and effect 70 complete removal of the scale.

In the various operations the scale is not left in the alveolar cavities but is drawn out by the cutting edge of the tool and the curved or upset end 20, of the tool prevents 85 laceration of the tissues.

In removing the scale from the molar as seen in Figs. 10 and 11 the adaptability of the tool is manifest particularly around the upper third between the roots, the scale being first removed by the application of the tool as seen in Fig. 1, the concave surfaces of the shank posterior to the cutting edge fitting the convex surface of the molar and in Fig. 11, the modification as seen at 22 in 95 Fig. 6 being adapted to fit the concave surface of the molar. In these varied forms in the construction of the tool I am enabled to reach the surfaces of all roots of teeth and remove all foreign substances and leave the dentine with a smooth polished surface without lacerating the surrounding tissue, and thus obviating the inflamed condition of the parts adjacent thereto thus offering the highest degree of resistance to the recurrence of the deposit on the tooth; the position of the cutting edge with the various modifications of the shank affording the most expeditious and efficient means of operating and securing results hitherto unattainable. Such other modifications may be employed as are within the scope of the invention.

Having fully described my invention what I now claim as new and desire to secure by 115 Letters Patent is,

1. A scale removing dental tool comprising a handle, a compound bent shank, and, adjacent the end of said shank, a cutting edge extending to and coincident with a line projecting from and extending through the longitudinal axis of the handle, said shank being formed adjacent the cutting edge with a guide surface which transversely comprises substantially straight line elements and which longitudinally conforms to the shape of the tooth surface to be operated upon and is adapted to rest thereon in contact with the tooth surface in such manner as to prevent the cutting edge from 120 125 130

scraping the dentine of the root of the tooth, the guide surfaces, cutting edge and the end of the shank beyond the cutting edge being so shaped that when cutting, the tool must rest upon the tooth at two points, one point being in the cutting edge and the other point being in the guide surface adjacent thereto, so that the tool must be operated by a drawing motion, the point of contact in the guide surface necessarily going ahead of the cutting edge, thus causing the tool to cut after the manner of a Japanese plane.

2. Tools for the treatment of teeth comprising a series of straight handles, each

tool adapted for use upon a predetermined shaped portion of the tooth and each having a cutting edge and a guiding portion, the guiding portion serving to engage with the tooth in advance of the cutting edge to steady the same, and the cutting edge being in the line of the axis of the handle whereby the instrument has no tendency to turn when in use, and planes as contradistinguished from scraping the surface.
